The ornamental design for a terminal for networks, as shown and described.

DESCRIPTION

FIG. 1 is a front perspective view of a terminal for networks, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the portion 8 encircled in dot-dot-dashed broken lines in FIG. 1;

FIG. 9 is an enlarged view of the portion 9 encircled in dot-dot-dashed broken lines in FIG. 1; and,

FIG. 10 is an enlarged view of the portion 10 encircled in dot-dot-dashed broken lines in FIG. 1.

The broken lines illustrating portions of the terminal for networks form no part of the claimed design. The dot-dot-dash broken lines encircling enlarged portions of the claimed design form no part of the claimed design.
